UNITED STATES PATENT OFFICE.

JAMES E. HENRY AND WILLIAM J. HENRY, OF REEDSVILLE, PENNSYLVANIA.

RAILWAY-TIE.

1,111,306.

Specification of Letters Patent.

Patented Sept. 22, 1914.

Application filed May 25, 1914. Serial No. 840,903.

To all whom it may concern:

Be it known that we, JAMES E. HENRY and WILLIAM J. HENRY, citizens of the United States, residing at Reedsville, in the 5 county of Mifflin, State of Pennsylvania, have invented a new and useful Railway-Tie, of which the following is a specification.

This invention relates to metallic railway ties, one of its objects being to provide a tie 10 of this character having means whereby rails secured thereto will be resiliently supported, the supporting means being simple, durable and efficient and including novel means whereby the rails are secured in place 15 without the use of fastening devices such as commonly employed.

Another object is to provide a railway tie which will not creep and serves positively to hold the rails against spreading.

With the foregoing and other objects in view which will appear as the description proceeds, the invention resides in the combination and arrangement of parts and in the details of construction hereinafter described 20 and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a view partly in elevation and partly in section of a tie embodying the present improvements, 35 the rails thereon being shown in section. Fig. 2 is a view partly in plan and partly in section of the structure shown in Fig. 1. Fig. 3 is a section on line A B Fig. 1, the rail and the cushioning means being shown 40 in elevation. Fig. 4 is a perspective view of the rail chair forming a part of the fastening and cushioning means. Fig. 5 is a view similar to Fig. 3 but showing a modified form of rail cushioning means. Fig. 6 45 is a perspective view of the cushioning block used in Fig. 5.

Referring to the figures by characters of reference 1 designates a hollow metallic tie having longitudinal and transverse ribs 2 upon the bottom thereof adapted to engage 50 the road bed and thus hold the tie against creeping. Formed in the bottom of the tie at any suitable points are drain openings 2' and ventilating openings 3 are formed in

the ends of the tie near the top thereof, these 55 ventilating openings being preferably inclined downwardly and outwardly. Thus it will be seen that any moisture which may enter the tie will be free to pass therefrom through the openings 2' and, by reason of the fact that air is free to circulate through the openings 3, it will be seen that the interior of the tie will be maintained in a dry condition.

The top of the tie is cut away near each 60 end, as shown at 4, the opening thus produced being extended throughout the width of the tie and being of a width substantially equal to the base of a rail R. The walls of the tie are thickened below the ends of the 65 openings 4 and are formed with pockets 5. Each pocket is adapted to receive a tongue 6 extending downwardly from a rail chair 7 which is in the form of an angular plate 70 adapted to fit snugly within the opening 4 and to project beyond the side walls of the tie. These tongues 6 are adapted to slide 75 upwardly and downwardly within the pockets 5 but are held against lateral movement by the walls of the pockets. Longitudinal 80 slots 8 are formed in the tongues and projecting through these slots are retaining bolts 9 or the like which extend through the pockets and into the walls of the tie. Thus the tongues 6 cannot be withdrawn 85 from the pockets unless the bolts 9 are first removed. The chair 7 is provided along its outer edge with a flange 10 designed to engage the outer base flange of the rail R mounted on the chair. Upstanding from 90 the bottom of the tie and directly under each of the openings 4 is a post 11 on which is mounted a coiled cushioning spring 12, the upper end of which bears against the 95 chair 7.

For the purpose of fastening rails to the chairs, devices such as shown in Figs. 1, 2 and 3 are employed. These fastening devices include a shank 13 adapted to be positioned under one of the extending terminal 100 portions of the chair 7 and provided, at one end, with a hook-shaped head 14 and, at its other end, with a threaded stem 15. This stem is adapted to project loosely through a jaw 16 having a hook-like head 17 while the said jaw is held against displacement relative to the shank 13 by means of a nut 18 or the like engaging stem 15. Obviously by

placing the hook 14 so that it will straddle one edge of the chair 7 and one of the base flanges and then adjusting the jaw 16 against the other edge of the chair so that its head 17 will engage the other base flange of the rail, and finally tightening the parts by means of the nut 18, the rail will be securely attached to the chair. Fastening devices of this type are adapted to be arranged 10 at each end of each chair, as shown particularly in Figs. 2 and 3.

It will be apparent that springs 12 will hold the chairs 7 and rails R normally elevated, the upward movement of the parts 15 being limited by the bolts 9 extending through the slots 8. When the rails are subjected to a weight, such as that exerted by a train passing thereover, the chair 7 will be pressed downwardly, thus causing 20 the tongues 6 to slide downwardly in the pockets 5 and causing the springs 12 to be placed under increased stress. Thus it will be seen that the rails are provided with resilient supports and the metallic tie body is 25 relieved from the jars and excessive vibrations to which it would otherwise be subjected and which would be likely to injure the tie.

Instead of using a spring cushioning element, such as hereinbefore described, a cushioning block 19 can be employed. One block is adapted to be inserted into each opening 4 and each block has its lower end tapered, as at 20 and adapted to be seated within a correspondingly shaped pocket 21 formed in the bottom of the tie. The upper end of the block has flanges 22 extending therefrom and designed to project over the side walls of the tie and up to the tongues 6 of the 40 chair 7. Where a cushioning block 19 is used, it becomes unnecessary to provide slots in the tongues and retaining bolts such as shown at 9. These cushioning blocks can be made of wood or any other desired material.

What is claimed is:—

1. A metallic railway tie having openings in the top thereof, there being guide pockets in the walls of the tie at the ends of the openings, a rail supporting chair movable downwardly into each opening, means extending from each chair and slidably mounted within the adjacent pocket, a cushioning element within the tie and under each chair, and means for fastening a rail to the chair. 45

2. The combination with a hollow metallic railway tie having openings in the top thereof extending throughout the width of the tie, of a chair movable downwardly into each of the openings, there being pockets in the walls of the tie adjacent the ends of the openings, tongues depending from the chairs and slidably mounted in the openings, cushioning means seated within the tie and under and supporting the chairs, and means for fastening rails to the chairs. 50

3. The combination with a hollow metallic railway tie having transverse openings in the top thereof, of a chair movable downwardly into each of the openings, tongues depending from the chair, there being pockets in the walls of the tie for the reception of the tongues, a cushioning element within the tie and under each of the chairs for supporting said chairs in raised positions, a rail engaging flange along the outer side of each 75 chair, the ends of the chair projecting beyond the tongues, and means engaging the projecting ends of the chair for securing a rail thereto. 70

In testimony that we claim the foregoing 80 as our own, we have hereto affixed our signatures in the presence of two witnesses.

JAMES E. HENRY.
WILLIAM J. HENRY.
